UNITED STATES PATENT OFFICE.

RÉNÉ F. DU COIN, OF CAMDEN, NEW JERSEY.

ELECTRIC SWITCH.

Application filed March 31, 1921. Serial No. 457,407.

To all whom it may concern:

Be it known that I, RÉNÉ F. DU COIN, citizen of the United States, residing at Camden, in the county of Camden and State 5 of New Jersey, have invented certain new and useful Improvements in Electric Switches, of which the following is a specification.

This invention relates to an improved foot 10 operated switch for alarm systems and seeks, among other objects, to provide a switch which will be positive in its operation and which, when closed, will be held closed so as to effect the continuous sounding of an 15 alarm until the switch is manually opened.

Other and incidental objects will appear hereinafter.

In the drawings:

Figure 1 is a plan view of my improved 20 switch, and

Figure 2 is a fragmentary side elevation of the switch, parts being broken away and illustrated in section.

In carrying the invention into effect, I 25 employ a base block 14 near one end of which is bolted an upstanding U-shaped post or bracket 15, the sides of the bracket being bent to provide laterally directed lugs 16 seating against the upper face of the block and receiving the bolts therethrough. Mounted to rock upon the bracket is a foot 30 lever 17 received between the sides of the bracket and extending through said sides and through the inner end portion of the lever is a pivot bolt 18. Near its outer end the lever is formed with a half turn and is offset downwardly toward the base block to provide a horizontally disposed foot piece 19 adapted to abut the block for limiting 35 the lever in its downward swinging movement and formed in the upper edge of the lever near its inner end is a notch defining a shoulder 20 disposed to cooperate with the bracket 15 for limiting the lever in its upward swinging movement. Suitably mounted 40 upon the base block beneath the lever 17 is a casing 21 in which are arranged coacting spring contacts 22 and projecting up-

wardly through the casing is a button 23 sustained by one of said contacts. At its 50 upper end, this button is formed with a notch or slot 23' freely receiving the lever 17 therein so that, as will be seen, the lever may be swung downwardly for depressing the button and flexing one of the contacts 55 22 into engagement with the other of said contacts for closing a circuit therethrough. Screwed or otherwise secured to the block 14 between the post 15 and casing 21 is a clutch member 24 having a pair of coacting upstanding resilient clutch fingers 25 disposed to receive the lever therebetween so that when the lever is depressed or swung downwardly said fingers will automatically engage the lever for holding the lever so depressed and consequently maintaining the 60 switch contacts 22 closed. As brought out in Figure 2, the block 14 is provided with an opening so that wires in circuit with an alarm may be readily connected with the 65 contact 22. Accordingly, since, when the lever 17 is depressed for closing the switch, the lever will be held in depressed position, the alarm will continue to sound until the lever is manually released.

Having thus described the invention, what 70 is claimed as new is:

In an alarm system, the combination of a base, a circuit closing push button mounted thereon, a bracket upstanding from the base, 80 a foot lever pivoted upon said bracket to extend across the push button and movable for depressing the button, the lever being offset to define a foot piece extending in close spaced relation to the base and engageable 85 therewith for limiting the lever when the button is depressed whereby to prevent crushing of the button, and a clutch member upstanding from the base beneath the lever between said bracket and the button and 90 having coacting resilient clutch fingers to receive the lever therebetween frictionally holding the lever when swung to depress the button.

In testimony whereof I affix my signature.

RÉNÉ F. DU COIN. [L.S.]
